UNITED STATES PATENT OFFICE

95,739

DESIGN FOR A SMOKER'S PIPE

Lynn M. Francis, Birmingham, Mich.

Application January 2, 1935, Serial No. 54,662

Term of patent 7 years

To all whom it may concern:

Be it known that I, Lynn M. Francis, a citizen of the United States, residing at Birmingham, in the county of Oakland and State of Michigan, have invented a new, original, and ornamental Design for Smokers' Pipes, of which the following is a specification, reference being made to the accompanying drawing, forming a part thereof.

Figure 1 shows a view from the top, the bowl having a slightly elongated shape, with the sides straightened out to meet in a point or angle on the center line longitudinally. From the bowl, the sides taper into the stem section, which is narrower than the bowl, and approximately straight for most of its length in this view. The stem section follows smoothly into the lines of the bit, or mouthpiece, of conventional type.

Figure 2 shows a direct side view, the bowl indicated setting at an angle, the center line of same being inclined away from the center line of the stem at the top. The top of the stem has a slight curvature lengthwise, and is very nearly

in line with the top of the bowl. The point formed by the sides of the bowl meeting at the outer extremity, as shown in the top view, Figure 1, follows down the bowl, around underneath, and along the lower line of the stem section of the bowl, fading out into a round section just before the wood joins the bit, or mouthpiece. The outer lower line of the bowl as in Figure 2, is a graceful curve, blending into the line of the bit.

Figure 3 shows the general appearance in perspective, looking from the bowl end, and from slightly above.

In the drawing, what has been called the bowl, together with its stem section, is indicated by the part with the lighter shading, and the bit or mouthpiece is indicated by the heavier shaded part. They are separated by the heavy line across the approximate middle of the pipe.

I claim:

The ornamental design for a smoker's pipe, as shown, and described.

LYNN M. FRANCIS.
